(57) **CLAIM**

The ornamental design for a display screen with graphic user interface, as shown and described.

DESCRIPTION

The file of this patent contains at least one drawing executed in color. Copies of this patent with color drawings will be provided by the Office upon request and payment of the necessary fee.

FIG. 1 is a front view of a first embodiment of a display screen with graphic user interface according to my new design;

FIG. 2 is a front view of a second embodiment thereof;

FIG. 3 is a front view of a third embodiment thereof;

FIG. 4 is a front view of a fourth embodiment thereof; and,

FIG. 5 is a front view of a fifth embodiment thereof.

The perimeters of the portion of the underlying portion of a display screen and the graphical user interface are understood to be flush.
